UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed March 25, 1920. Serial No. 368,691.

My invention relates to improvements in locomotive boilers having internal fireboxes and equipped with water elements that assist in steaming and circulating the boiler water; and in particular, the invention relates to improvements in the locomotive boilers which contain the thermic siphons, so called, originated by John L. Nicholson, of Chicago, Illinois.

The thermic siphon, as generally constructed by him, comprises a stay-bolted water-wall of generally inverted-triangular shape in side elevation; arranged longitudinally in the firebox of the locomotive, with its top opening through the crown sheet thereof, and at its lower end presenting an intake neck which opens through the lower part of the flue sheet or throat sheet of the firebox. Such Nicholson siphons, by thermal action, pump a great volume of water from the lower part of the boiler and deliver the water and steam into the space above the crown sheet; with many attendant advantages.

Similarly, a group of ordinary arch tubes, opening out of the throat sheet of the firebox and extending thence into or communicating with the space at the top of the boiler, operate to take a large volume of water from the throat or front water leg of a locomotive boiler.

I have discovered that, in both cases, the forcible exhausting of water from the front leg or throat of the boiler tends to interrupt, complicate and disturb the normal flow or currents of water needed to supply the side and back water legs of the boiler. This disturbance has little observable effect in a boiler that has a generously large throat portion, in free communication with the barrel of the boiler; but in many cases, the interruption or diversion of the currents that should normally flow to the sides and back of the boiler along the mud-ring of the firebox and thence upwardly, results in the cracking of firebox sheets and the loosening of many staybolts. The incidental effects are an increased cost of boiler maintenance and the interruption of service.

Such cases are sufficiently common to make the problem of retaining the normal circulation a serious one; and as apparent from the history of various circulating systems, a problem that has been difficult of solution.

I have found the solution, in a system and

practicable construction whereby the demand of the water circulating elements is supplied from a point in the boiler barrel so far removed from the firebox as to leave undisturbed the normal and adequate flow of water to the water legs; making the operation of the circulating elements separate from and independent of those portions of the front water leg through which the other water spaces are supplied.

Doubtless my invention will be understood from this brief statement, but I shall set it forth in greater detail, along with a description of the best ways of embodying the invention in a locomotive boiler.

Proceeding to another phase of the invention:—A full length longitudinal circulation of the water in a locomotive boiler is essential to the economical maintenance thereof. While the circulating devices above mentioned tend to hasten the longitudinal circulation of the water in the boiler, I find that their operation so strongly localizes the circulation as to result in an eddying stagnation of the water in the forward end of the boiler, preventing the development of its full efficiency.

Hence, my invention has for its further object the provision of means that will enforce the longitudinal circulation of the water, to any extent desired. I accomplish this through the extension and agency of the same means that I employ for separating the operation of the main parts of the firebox from the important, but relatively minor, operation of the water circulating elements.

As well known, the operation of a locomotive boiler is frequently interfered with by the leaking of the flue sheet and flues; brought about by differences of expansion and contraction in the upper and lower parts of the boiler. My invention corrects this fault by diverting the intermittently supplied cold feed-water from the flue sheet, and providing a path or channel through which all, or the greater part, of the feed-water is conducted directly to the water circulating element or elements there to be heated, and thus conditioned for reception in the main body of boiler water; whereby the lower flues and flue sheet are relieved from the sudden changes of temperature that have been the cause of the trouble. Also, as will be evident, I thus convert the water circulating element into an in-

ternal feed water heater, and better insure a substantially uniform temperature throughout the boiler.

In this respect my invention finds its best embodiment in locomotive boilers that are equipped with the Nicholson thermic siphon, which in itself includes means for absorbing the varying contraction and expansion induced by the intermittent entrance of the feed water; and furthermore has stay-bolted sides which, being exposed to equal temperatures within the firebox, are not injured by temperature variations which would disrupt the sheets and stay-bolts composing the main water legs of the boiler.

Further, my invention has to do with the operative connection of the essential parts, to the water circulating elements, all in simple and economical form; and preferably, without mechanical dependence upon, or attachment to, the fire sheets of the firebox, to the end that the latter and the boiler shell shall not be required to sustain added or unusual stress and strains.

Other important objects and purposes of my invention will appear hereinafter, together with the detailed description of the manner in which they are attained.

Since putting my completed invention into practical and successful use in this country I have learned of the existence of earlier proposed locomotive boiler designs involving crudely constructed water elements that for a brief time might cause a limited circulation of water from the forward part of the boiler, through the firebox and thence into the space above the crown sheet; but exhibiting no knowledge of the matters herein discussed, and which have been found to be wholly unworkable; and for practical purposes, they have been, and still may be, treated as non-existent.

My invention will be more readily understood on reference to the drawings that form part of this specification, and in which—

Fig. 1 is a longitudinal vertical section of a locomotive boiler embodying my invention.

Fig. 2 is a fragmentary plan view of the lower part of the boiler.

Fig. 3 is an enlargement (on the line 3—3 of Fig. 4) of the throat or front water leg of the boiler, showing the preferred telescopic connection between the intake end of the water circulating element and the intake channel or duct in the bottom of the boiler.

Fig. 4 is a vertical elevation, showing the channel head through an opening in the flue sheet as though the element and diaphragmatic flange were removed.

Figs. 5, 6 and 7 are vertical cross sections of rear ends or firebox portions of three typical designs, known respectively as narrow, medium width and wide fireboxes, and containing respectively, one, two and three of said Nicholson thermic siphons.

Fig. 8 is a horizontal section on the line 8—8 of Fig. 5.

Fig. 9 is a vertical section on the line 9 of Fig. 6.

Fig. 10 is a vertical section on the line 10 of Fig. 7.

Fig. 11 is a vertical longitudinal section of a locomotive boiler containing a firebox of the combustion chamber type and constructed in accordance with my invention. 75

Fig. 12 is a vertical section, mainly on the line 12 of Fig. 11, but with parts broken away on the line 12^a of Fig. 11.

Fig. 13 is another view of the combustion chamber firebox and boiler, showing my invention in modified form. 80

Fig. 14 is a like view, but illustrating an extension of the intake channel.

Fig. 15 is an enlarged cross section of the intake portion of Fig. 13, modified in respect 85 to the head or throat portion of the intake channel.

Fig. 16 is a cross section partly on the line 16—16 of Fig. 13 and partly on the line 16^a of Fig. 13. 90

Fig. 17 is a similar section, but looking rearward, from the line 17—17 of Fig. 14.

Fig. 18 illustrates a modified intake head or throat portion which permits the washing of the mud ring of the firebox from side to side; 95 and

Fig. 19 is a sectional detail showing a portion of my novel construction as it appears in a boiler which has the bottom of its barrel and its mud ring more nearly in a single 100 horizontal plane, so that the head or telescoping end of the intake channel need not be so immediately a part or division of the throat or front water leg of the boiler.

A locomotive boiler is constructed entirely 105 of metal and is of the horizontal type. Thus each boiler herein depicted comprises a long cylindrical barrel or body portion, 1; a "front-end" or smoke box, 2, with stack, 3; a "rear-end" or firebox portion, 4; and, a large 110 number of fire flues 5. The sheet, 6, which separates the barrel 1 from the smoke box 2, is called the front flue sheet. The "rear-end" of the boiler is a substantially rectangular extension of the body thereof and contains 115 the internal firebox. Usually it is bottomed by a so-called mud ring 7 which aids in defining the water legs of the boiler, to wit, the rear leg 8, the side legs 9, 9, and the front leg or throat 10. The sheets comprising the internal firebox are, the back sheet 11, the side sheets 12, 12, the crown sheet 13 and the rear flue sheet 14. According to type, the flue sheet may be as in Fig. 1, with a throat portion 15, that is a downward extension of the 120 flue sheet 14; or as in Figs. 11, 13 and 14 the rear flue sheet may be set forward from the firebox proper through the interposition of a combustion barrel 16, while the throat portion 15 remains at the mud ring. The outer 125 portion 15 remains at the mud ring. The outer 130

sheets of the rear-end are parts of the boiler shell. As is made necessary by the pressure in the boiler, the fire sheets 11, 12, 13 and 15 are joined to respectively opposed portions of the boiler shell by a large number of spaced stay bolts. These clearly appear in the several sectional views, with the exception of Figs. 13 and 14 where only those immediately associated with the intake channel of this invention are shown. The grate that usually forms the bottom of the firebox is not shown. Each firebox herein shown contains one or more Nicholson thermic siphons, marked S, each of which constitutes a water steaming and circulating element. Each has an intake neck, S', which opens through the throat sheet 15, and in each case the portion of the throat sheet immediately surrounding the neck comprises an expansion and contraction diaphragm. As shown the siphons are of substantially inverted-triangular form, and at the top communicate with the boiler space through extensive slot-like openings S" in the crown sheet 13 of the firebox. When in action, with a hot fire in the firebox, these siphons pump large volumes of water from the lower part of the boiler, convert much of it into steam, and deliver the steam and remaining water into the top of the boiler. Ordinary arch tubes, not shown, act similarly; and in this case the thermic siphons are representative of all types of water circulating devices which take water from the throat portion of the boiler and, except as supplemented herein, tend to set up detrimental currents in the other water spaces, as before elucidated.

The feed water enters the boiler through the so-called boiler-check valve 17, usually arranged either at the top of the boiler as shown in Fig. 1 or on the side, as in Figs. 11, 13 and 14. The steam leaves the boiler from the dome 18, passing out through a dry-pipe, not shown, at the opening 19 in the front flue sheet.

The parts by which the objects of my invention are accomplished are arranged in the bottom of the body of the boiler and preferably comprise a separate intake channel, C, for each boiler circulating element S. The channel preferably comprises an inverted trough 20, made of thin sheet metal (obviously it is not subjected to destructive pressure), and which trough rests upon the bottom of the boiler shell. This channel is open at its forward end 21, and leads backward to the throat sheet 15, terminating in an intake head 22. The latter presents an opening 23, which is in registry with the open end of the intake neck of the circulating element S. The trough may be either strapped or spot-welded in place. Preferably, the parts 20 and 22 are joined by welding them on the mitre line 20'.

The cross-sectional area of the intake trough or channel 20 exceeds that of the in-

take neck of the circulating element and therefore is of ample capacity. The water flowing therethrough attains its greatest velocity in the Venturi-like nozzle portion 22' of the head 22, which nozzle marks the point 70 where the passage is constricted.

As well shown in Fig. 3 the nozzle portion 22' of the intake head enters the lower end of the circulating element, and it is in telescopic connection therewith. Also, as shown in 75 Fig. 3 the nozzle 22' is a little smaller, a minute crack remaining between it and the inner wall of the intake neck S'. In other words the telescopic connection is a leaky one, the purpose being to permit a constant slight 80 inrush of water at this point directly from the throat of the boiler whereby the rusting together of the metal parts is prevented; also to prevent the accumulation of scale between them. 85

The intake head is of trough-like shape in horizontal cross section, see Figs. 2, 4 and 8, and its edges are fastened to the boiler shell. It makes a convenient mitre joint connection 20' with the trough-like part 20, but its curved exterior is more especially for the purpose of keeping the end surface 22" of the head separated as widely as possible from the adjacent throat sheet 15. In this way I avoid places for the collection of mud and scale, which might 90 result in the cracking and burning of the throat sheet and interfere with the action of its corrugated or diaphragmatic portion 15'.

The intake head has a closed bottom 22^a with the result that except for slight leaks between its edges and the boiler plates the intake channel is limited to communication, at its forward end, with the body of the boiler and to communication with the water circulating element, at its rear end. 100

One advantage of the described construction is that it does not interfere with the presence and use of a washout opening and plug 24 in the outside throat sheet of the boiler shell. When the plug is removed both the 110 interior of the intake head and the interior of the water circulating element become accessible for purposes of inspection and washing.

As to the remainder of the circulating element, it will be noted that washout plugs are 115 provided in the back head of the shell and also in the top wrapper sheet, directly above the open top of the element S.

One or more washout plugs 25 may be arranged in the bottom of the boiler, either 120 within, or in line with the intake channel C to facilitate the washing thereof.

It will be evident that by the means described I effectively divide the throat 10 of the boiler in separate portions, leaving large 125 undisturbed passages into the side legs of the firebox, and prevent the suction of the water circulating elements from setting up any contrary movement of water currents from the side water legs and into the water circulating 130

elements. The movement of water through the leaky connections herein described does not materially affect the division and movement of the greater body of water through the boiler throat and into the side legs.

The strong movement of water rearwardly along the bottom of the boiler barrel from a point near the front flue sheet, results in a full longitudinal circulation of the water, the currents conforming substantially to those indicated by the many arrows in Fig. 1. The effect is to increase the efficiency of the boiler and lessen the cost of maintenance.

The feed water which enters through the boiler-checks or valves 17, by reason of its low temperature and greater density, sinks to the bottom of the boiler and accepts the path of movement offered by the intake channel or channels C, through which water is moving at high velocity. Thus all or the greater part of the feed water is diverted from the flue sheet, 14—15, and is conducted to the element or elements S, wherein its temperature is quickly raised.

One advantage of the specially designed intake heads herein shown is that they do not reach down as far as the mud-ring of the firebox and, therefore, do not interfere with the washing-across of the mud-ring at times when the boiler is cleaned.

A further advantage of the described intake channel construction is that it is not costly; and further, it does not interfere with, nor make difficult the installation of the flues, 35 or the stay-bolts 15", which immediately surround the intake of the water circulating element. Whenever necessary the stay-bolts may be passed directly through parts of the intake channel and head, as indicated in Figs. 40 3, 4, 11 and 12.

In the case of a boiler equipped with Nicholson siphons, these head and channel troughs are of special convenience because they are extremely easy to install while the siphon 45 diaphragm hole is open in the throat sheet, and before the siphon and diaphragm are welded in place.

The objects of my invention may be accomplished in ways other than those next above 50 detailed; for examples of which, attention is directed to Figs. 13 to 19.

In Figs. 13 to 18 I have illustrated a common intake head for two or more water circulating elements. This intake head is 55 formed by partitions 22^b that divide the throat 10' into separate compartments, defining a middle space in communication with the intakes of the several siphons S. The partitions 22^b have extensions 20^a at the top 60 that pass forward beneath a combustion barrel of the firebox, being arranged between the rows of stay-bolts 26 belonging thereto. These parts 20^a may terminate at the forward end of the combustion barrel, as shown in 65 Fig. 13, but preferably are extended, as

through the medium of the inverted trough-like member 20^b, as shown in Fig. 14.

In both forms of the intake head, it will be noticed that the parts are attached to the boiler shell, and that there is no mechanical connection with the fire sheets of the firebox; hence they are not affected by, and do not limit the expansion and contraction thereof.

Usually the partitions 22^b extend down to the mud-ring, as shown in Figs. 16 and 17, 75 and additional washout plugs 27 are provided to insure the thorough cleaning of the intake head. The plugs 28, shown in Figs. 16, 17 and 18, close the ordinarily positioned mud-ring washout holes. If it is desired 80 the use of the extra plugs 27 may be avoided by leaving spaces 29 beneath the partitions 22^b, as shown in Fig. 18, or by providing the head with a floor 22^c, as shown in Fig. 15. However, if that floor is much lower than the 85 bottom of the intake neck S' it will be found expedient to use an additional washout plug 30 therein.

As illustrated in Fig. 19 there are some 90 boilers having barrels of great diameter and which so limit the depth of throat that to preserve sufficient firing clearance beneath the water circulating elements, the elements are made to enter the throat sheet substantially 95 on a level with the bottom of the water barrel. In such cases, as shown, the depending portion of the intake head need be preserved only where necessary to admit the washout plug 31; and the intake channel 32 becomes 100 virtually a straight duct leading from the front of the boiler to the water circulating element. As before, it is desirable to maintain a telescopic joint 33 at this point.

Various modifications of my invention will 105 readily suggest themselves to one skilled in the art, and I do not limit my claims to the specific structures herein shown and described.

In certain of the claims the phrase "said 110 conduit extending forward and having an intake from the barrel of the boiler substantially removed from the throat of the firebox" is used. This phrase is intended to imply that the intake of the conduit is substantially removed from the throat of the firebox so 115 that it will not receive the water from the throat or adjacent water legs of the firebox, but on the other hand will receive the relatively cooler water which is found forwardly of that point, with a resulting increase in 120 efficiency of the parts.

Having thus described my invention, I claim as new and desire to secure by Letters Patent:—

1. The herein described locomotive boiler 125 having a fire box formed with side water legs and a throat, a water-steaming and circulating element arranged in the fire-box and having an inlet end connected to the throat, in combination with parts that divide a por- 130

tion of the fire-box throat from those portions of the throat through which the side water legs communicate with the body of the boiler, said parts being spaced from but in communication with the inlet end of said water steaming and circulating element.

2. The herein described locomotive boiler having a fire box formed with side water legs and a throat, a water-steaming and circulating element arranged in the fire-box and having an inlet end connected to the throat in combination with parts that divide a portion of the fire-box throat from those portions of the throat through which the side water legs communicate with the body of the boiler, said parts being spaced from but in communication with the inlet end of said water steaming and circulating element, and another part positioned in the body of the boiler and formed to direct water from the forward portion thereof into the said parts that divide the throat and communicate with the water steaming and circulating element.

3. The herein described locomotive boiler having a fire box formed with side water legs and a throat, a plurality of water-steaming and circulating elements arranged in the fire-box and having inlet ends connected with the throat, in combination with a plurality of intake members located in the throat and in communication with the inlet ends of respective water steaming and circulating elements but spaced therefrom, and intake channels positioned in the body of the boiler, communicating with said intake members and formed to direct water from the forward part of the boiler to respective members.

4. The herein described locomotive boiler having a fire box formed with side water legs and a throat, a water-steaming and circulating element positioned in the fire-box and having its intake connected to the throat, in combination with an intake head arranged in the throat, and telescopically aligned with but spaced from the intake of the water-steaming and circulating element, and an intake duct positioned in the body of the boiler for directing water into said intake head.

5. The herein described locomotive boiler having a fire box formed with side water legs and a throat, a water-steaming and circulating element positioned in the fire-box and having its intake adjacent the throat in combination with an intake channel positioned entirely within the boiler open at one end into the boiler space forward of said throat and having its other end telescopically aligned with but spaced from the intake of said water steaming and circulating element.

6. The herein described locomotive boiler having a fire-box formed with side water legs and a throat, a water-steaming and circulating element positioned in the fire-box and having its intake connected with the throat, in combination with washout means, and an

element supply intake head arranged in the throat operatively connected to the boiler space forward of the throat and communicating with but spaced from the intake of the water-steaming and circulating element and rising above said washout means.

7. The herein described locomotive boiler having a fire box formed with side water legs and a throat, a water-steaming and circulating element arranged in the fire-box and having its intake connected with the throat, an intake head arranged in the throat and loosely connected with the intake of said water-steaming and circulating element, and an intake channel in the body of the boiler and communicating with said head.

8. The herein described locomotive boiler having a fire-box formed with side water legs and a throat, a water-steaming and circulating element arranged in the fire-box and having its intake connected adjacent the throat in combination with parts that divide that portion of the fire-box to which the intake of the water-steaming and circulating element is connected from those portions through which the side water legs communicate with the body of the boiler, said parts being spaced from but in communication with the inlet of said water steaming and circulating elements.

9. The locomotive boiler and contained firebox, in combination with a water-steaming and circulating wall in said firebox and having an intake which opens into the throat of the boiler through the throat sheet of the firebox, an intake head secured in the boiler throat and loosely connected with the intake of said element, and an intake channel in the boiler body and leading to said head.

10. A locomotive boiler and contained firebox having a throat sheet, in combination with a water circulating element in said box and connected to the throat sheet, an intake head in the throat of the boiler and in communication with but spaced from the lower end of said water circulating element, and an intake channel located entirely within the boiler and leading from the forward end thereof, backward to and communicating with said intake head.

11. A locomotive boiler and its contained firebox, the firebox having a throat, embodying therein a relatively flat hollow water circulating and steaming element positioned in a plane other than horizontal and composed of spaced plates stay-bolted together, said element having an upper portion and a lower portion, the lower portion being closed and the upper portion having an elongated opening longitudinally of the firebox and being connected to one of the firesheets of the firebox to thereby communicate with the adjacent water space, a conduit of relatively restricted cross sectional area communicating directly with the lower part of said water circulating

and steaming element, said conduit extending forward and having an intake from the barrel of the boiler substantially removed forwardly from the firebox tube sheet.

- 5 12. A locomotive boiler and its contained firebox, the firebox having a throat, embodying therein a relatively flat hollow water circulating and steaming element positioned in a plane other than horizontal and composed 40
10 of spaced plates stay-bolted together, said element having an upper portion and a lower portion, the lower portion being closed and the upper portion having an elongated opening longitudinally of the firebox and being 45
15 connected to one of the firesheets of the firebox to thereby communicate with the adjacent water space, a conduit of relatively restricted cross sectional area communicating directly with the lower part of said water 50
20 circulating and steaming element, said conduit extending forward and having an intake from the barrel of the boiler substantially removed forwardly from the firebox tube sheet, the lowermost part of the water 55
25 circulating and steaming element being below the conduit inlet from the barrel of the boiler, and a washout plug positioned in said lower plane for flushing the said bottom portion of the water circulating and steaming element. 60
30 13. A locomotive boiler and its contained firebox, the firebox having a throat, embodying therein a relatively flat hollow water circulating and steaming element positioned in 65
35 a plane other than horizontal and composed of spaced plates stay-bolted together, said element having an upper portion and a lower portion, the lower portion being closed by an enlarged bulging portion and the upper por- 70
75

tion having an elongated opening longitudinally of the firebox and being connected to one of the firesheets of the firebox to thereby communicate with the adjacent water space, a conduit of relatively restricted cross sectional area communicating directly with the enlarged bulging lower part of said water circulating and steaming element, said conduit extending forward and having an intake from the barrel of the boiler substantially removed forwardly from the firebox tube sheet. 50

14. A locomotive boiler and its contained firebox, the firebox having a throat, embodying therein a relatively flat hollow water circulating and steaming element positioned in a plane other than horizontal and composed 55
55 of spaced plates staybolted together, said element having an upper portion and a lower portion, the lower portion being closed and the upper portion having an elongated opening longitudinally of the firebox and being 60
60 connected to one of the firesheets of the firebox to thereby communicate with the adjacent water space, an end of the lower part of the water circulating and steaming element having a flange, a conduit of relatively 65
65 restricted cross sectional area communicating directly with the lower part of said water circulating and steaming element and being operatively fitted adjacent said flange, said conduit extending forward and having an intake 70
70 from the barrel of the boiler substantially removed forwardly from the firebox tube sheet.

In testimony whereof I have affixed my signature at Washington, D. C., March 22nd, 75
1920.

CHARLES GILBERT HAWLEY.
